(57) **ABSTRACT**

A new and distinct cultivar of *Chrysanthemum* plant named 'Zanmulpine Yellow', characterized by its upright, outwardly spreading and uniformly spherical plant habit; vigorous growth habit; freely branching habit, dense and full plant habit; dark green-colored leaves; uniform and freely flowering habit; long flowering period; decorative-type inflorescences with ray florets that are light yellow in color; and good garden performance.

1 Drawing Sheet

1

Botanical designation: *Chrysanthemum X morifolium*.
Cultivar denomination: 'ZANMULPINE YELLOW'.

BACKGROUND OF THE INVENTION

The present invention relates to a new and distinct cultivar of *Chrysanthemum* plant, botanically known as *Chrysanthemum X morifolium*, commercially referred to as a Garden Mum and hereinafter referred to by the name 'Zanmulpine Yellow'.

The new *Chrysanthemum* plant is a product of a planned breeding program conducted by the Inventor in Rijsenhout, The Netherlands. The objective of the breeding program is to create new uniform spherically-shaped and freely flowering *Chrysanthemum* plants with unique and attractive ray floret coloration.

The new *Chrysanthemum* plant is a naturally-occurring whole plant mutation of *Chrysanthemum x morifolium* 'Zanmulpine', disclosed in U.S. Plant Pat. No. 30,154. The new *Chrysanthemum* plant was discovered and selected as a single flowering plant from within a population of plants of 'Zanmulpine' in a controlled greenhouse environment in Rijsenhout, The Netherlands in July, 2014.

Asexual reproduction of the new *Chrysanthemum* plant by vegetative terminal cuttings was first conducted in a controlled greenhouse environment in Rijsenhout, The Netherlands since September, 2014. Asexual reproduction by vegetative terminal cuttings has shown that the unique features of this new *Chrysanthemum* plant are stable and reproduced true to type in successive generations.

SUMMARY OF THE INVENTION

The following traits have been repeatedly observed and are determined to be the unique characteristics of

2

'Zanmulpine Yellow'. These characteristics in combination distinguish 'Zanmulpine Yellow' as a new and distinct *Chrysanthemum* plant:

- 5 1. Upright, outwardly spreading and uniformly spherical plant habit; vigorous growth habit.
2. Freely branching habit; dense and full plant habit.
3. Dark green-colored leaves.
4. Uniform and freely flowering habit.
- 10 5. Long flowering period.
6. Decorative-type inflorescences with ray florets that are light yellow in color.
7. Good garden performance.

Plants of the new *Chrysanthemum* can be compared to plants of the mutation parent, 'Zanmulpine'. Plants of the new *Chrysanthemum* differ primarily from plants of 'Zanmulpine' in ray floret color as plants of the new *Chrysanthemum* have light yellow-colored ray florets whereas plants of 'Zanmulpine' have white-colored ray florets.

Plants of the new *Chrysanthemum* can also be compared to plants of *Chrysanthemum X morifolium* 'Zanmumadore Yellow', disclosed in U.S. Plant Pat. No. 31,021. In side-by-side comparisons, plants of the new *Chrysanthemum* differ primarily from plants of 'Zanmumadore Yellow' in the following characteristics:

- 25 1. Plants of the new *Chrysanthemum* have larger inflorescences than plants of 'Zanmumadore Yellow'.
2. Ray florets of plants of the new *Chrysanthemum* are lighter yellow in color than ray florets of plants of 'Zanmumadore Yellow'.

BRIEF DESCRIPTION OF THE PHOTOGRAPH

The accompanying photograph illustrates the overall appearance of the new *Chrysanthemum* plant showing the colors as true as it is reasonably possible to obtain in colored

reproductions of this type. The photograph comprises a top perspective view of a typical flowering plant of 'Zanmulpine Yellow' grown in a container.

DETAILED BOTANICAL DESCRIPTION

The aforementioned photograph and following observations and measurements describe plants grown in 17-cm containers in an outdoor nursery in Rijshout, The Netherlands under natural daylengths during the summer and autumn and under cultural practices generally used in commercial *Chrysanthemum* production. During the production of the plants, day temperatures ranged from 15° C. to 25° C. and night temperatures ranged from 8° C. to 15° C. Plants were 19 weeks from planting when the photograph was taken and the detailed description was taken on plants from 16 to 20 weeks after planting. In the following description, color references are made to The Royal Horticultural Society Colour Chart, 2015 Edition, except where general terms of ordinary dictionary significance are used.

Botanical classification: *Chrysanthemum* X *morifolium* 'Zanmulpine Yellow'.

Parentage: Naturally-occurring whole plant mutation of *Chrysanthemum* x *morifolium* 'Zanmulpine', disclosed in 25 U.S. Plant Pat. No. 30,154.

Propagation:

Type cutting.—By vegetative tip cuttings.

Time to initiate roots, summer.—About six to eight days at temperatures about 12° C. to 23° C. 30

Time to produce a rooted young plant, summer.—About 12 to 13 days at temperatures about 12° C. to 23° C.

Root description.—Fine, fibrous; typically close to 164D in color, actual color of the roots is dependent 35 on substrate composition, water quality, fertilizer type and formulation, substrate temperature and physiological age of roots.

Rooting habit.—Freely branching; dense.

Plant description:

Appearance.—Perennial decorative-type *Chrysanthemum*; stems upright and outwardly spreading giving a uniformly rounded appearance to the plant; plants spherical in overall shape; very freely branching habit, about nine to ten primary lateral branches 45 develop, each primary lateral branch with about ten secondary branches; dense and full plant habit; vigorous growth habit and rapid growth rate.

Plant height.—About 35 cm.

Plant width.—About 60 cm.

Lateral branches.—Length: About 18 cm to 20 cm. Diameter: About 1.5 mm to 2 mm. Internode length: About 2 mm to 4 mm. Strength: Moderately weak. Aspect: About 30° to 45° from vertical. Texture and luster: Pubescent; longitudinally ridged; matte. 55 Color: Close to 138B; with development, becoming closer to 199A.

Leaves.—Arrangement: Alternate, simple. Length: About 1.8 cm to 5.8 cm. Width: About 0.8 cm to 3.4 cm. Shape: Elliptic to broadly elliptic. Apex: Acute. 60 Base: Attenuate. Margin: Palmately lobed, sinuses between lateral lobes divergent and medium in depth. Texture and luster, upper surface: Pubescent; slightly glossy. Texture and luster, lower surface: Pubescent; matte. Venation: Pinnate. Color: Developing leaves, upper surface: Close to 143A. Devel-

oping leaves, lower surface: Close to 138A. Fully expanded leaves, upper surface: Close to 137A; venation, close to 147A. Fully expanded leaves, lower surface: Close to 138A; venation, close to 148D. Petioles: Length: About 6 mm to 8 mm. Diameter: About 2 mm. Strength: Moderately strong. Texture and luster, upper and lower surfaces: Pubescent; semi-glossy. Color, upper surface: Close to 147A. Color, lower surface: Close to 148D.

Inflorescence description:

Appearance.—Decorative-type inflorescence form; inflorescences borne on terminals above foliar plane; ray florets arranged acropetally on a capitulum; inflorescences facing upright to outwardly.

Fragrance.—Faintly fragrant, pungent.

Flowering response.—Under natural season conditions, plants flower from week 41 to week 45 in The Netherlands.

Postproduction longevity.—Inflorescences maintain good color and substance for about three weeks in an outdoor nursery; inflorescences persistent.

Quantity of inflorescences.—About 800 inflorescences develop per plant.

Inflorescence buds.—Height: About 2 mm. Diameter: About 4 mm. Shape: Rounded. Texture and luster: Pubescent; semi-glossy. Color: Close to 150D.

Inflorescence diameter.—About 4 cm.

Inflorescence depth (height).—About 1 cm to 3 cm.

Disc diameter.—To date, disc floret development has not been observed on plants of the new *Chrysanthemum*.

Receptacle diameter.—About 3 mm.

Receptacle height.—About 3 mm.

Receptacle shape.—Domed.

Receptacle color.—Close to 138B to 138C.

Ray florets.—Number of ray florets per inflorescence: About 200 to 220 ray florets arranged in about ten whorls. Length, developing: About 0.8 cm. Length, developed: About 2 cm. Width, developing: About 1 mm. Width, developed: About 4 mm. Shape, developing: Narrowly elliptic. Shape, developed: Elliptic. Apex, developing and developed: Acute. Base, developing and developed: Attenuate. Margin, developing and developed: Entire; not undulate. Aspect, developing and developed: Mostly flat. Texture and luster, developing and developed, upper and lower surfaces: Smooth, glabrous; slightly glossy. Color: When opening, upper surface: Close to 8A. When opening, lower surface: Close to 8C. Fully opened, upper surface: Close to 3C; color becoming closer to 11A with development. Fully opened, lower surface: Close to 8D; color becoming closer to 11C with development.

Phyllaries.—Number of phyllaries per inflorescence: About 24 phyllaries arranged in about three whorls. Length: About 6 mm. Width: About 1.5 mm. Shape: Narrowly elliptic. Apex: Acute. Base: Attenuate. Margin: Entire. Texture and luster, upper and lower surfaces: Pubescent; semi-glossy. Color, upper surface: Close to 139A. Color, lower surface: Close to N138B.

Peduncles.—Length, terminal peduncle: About 7.5 cm. Length, third peduncle: About 6 cm. Diameter, terminal peduncle: About 1.5 mm. Diameter, third peduncle: About 1.2 mm. Strength: Moderately strong. Texture and luster: Pubescent; matte. Color: Close to 138B.

Reproductive organs.—Androecium: Not observed. Gynoecium: Number of pistils per ray floret: One. Pistil length: About 4 mm. Style length: About 3.8 mm. Style color: Close to 154C. Stigma diameter: About 0.5 mm. Stigma shape: Forked. Stigma color: Close to 7A. Ovary color: Close to 149D.

Seeds and fruits.—To date, seed and fruit production have not been observed on plants of the new *Chrysanthemum*.

Garden performance: Plants of the new *Chrysanthemum* have demonstrated good garden performance and will tolerate temperatures ranging from about 4° C. to about 30° C.

It is claimed:

1. A new and distinct *Chrysanthemum* plant named 'Zanmulpine Yellow' as illustrated and described.
